United States Patent Office

Des. 225,599
Patented Dec. 26, 1972

225,599

CHAIR

Stanley H. Hutchinson, Sierra Madre, Calif., assignor to David E. Vaughn, Owosso, Mich.

Filed Mar. 22, 1971, Ser. No. 127,065

Term of patent 14 years

Int. Cl. D6—02

U.S. Cl. D6—55

FIG. 1 is a front perspective view of a chair showing my new design;

FIG. 2 is an elevational view of one side of the chair illustrated in FIG. 1;

FIG. 3 is an elevational view of the other side of the chair illustrated in FIG. 1;

FIG. 4 is a top plan view of the chair illustrated in FIG. 1;

FIG. 5 is a front elevational view of the chair illustrated in FIG. 1; and

FIG. 6 is a rear elevational view of the chair illustrated in FIG. 1.

I claim:
The ornamental design for a chair, as shown.
